Patented July 10, 1917.

UNITED STATES PATENT OFFICE.

JULIUS T. FREY, OF DETROIT, MICHIGAN.

ASH-SIFTING MACHINE.

1,232,784.

Specification of Letters Patent. Patented July 10, 1917.

Application filed October 3, 1916. Serial No. 123,556.

To all whom it may concern:

Be it known that I, JULIUS T. FREY, a citizen of the United States, residing at Detroit, in the county of Wayne and State 5 of Michigan, have invented certain new and useful Improvements in Ash-Sifting Machines, of which the following is a specification.

This invention relates to devices for sifting 10 ashes and for like purposes, and has for one of its objects to improve the construction and increase the efficiency and utility of devices of this character.

With these and other objects in view, the 15 invention consists in certain novel features of construction as hereinafter shown and described and then specifically pointed out in the claims, and in the drawings illustrative of the preferred embodiment of the invention.

Figure 1 is a vertical transverse sectional elevation;

Fig. 2 is a longitudinal sectional elevation;

Fig. 3 is a detached perspective view on a reduced scale, of the loading hopper.

Fig. 4 is a sectional detail on a reduced scale, illustrating a modification in the construction.

Corresponding and like parts are referred to in the following description and indicated in all the views of the drawings by the same reference characters.

The improved device comprises a casing 35 or shell, represented as a whole at 10, and constructed preferably of galvanized sheet metal and having a relatively large opening 11 in the upper end and with the bottom entirely open. The opening 11 is provided 40 with a closure 12 hingedly united at 13 to the casing. The casing is provided with a relatively large opening 14 in the front and preferably provided with a sliding closure 15 operating in guideways, one of which is 45 represented at 16. The opening 14 does not extend to the bottom of the casing but stops short thereof, and located within the casing below the lower line of the opening 14 is a receptacle 17 having a bottom 17 of screen 50 material.

Mounted for rotation through the casing is a shaft 18 having an operating crank 19 at one end externally of the casing. Mounted upon the shaft 18, within the casing, is a 55 screening drum comprising imperforate

ends 20 and a cylinder of screen material 21, the screen material being supported upon the ends 20 by holding bands 22. Mounted upon the shaft 18 between the ends 20 of the drum and the adjacent walls of the casing 10 are spacing washers 23. Mounted upon the shaft 18 between the ends 20 of the drum is a tubular axle 24 having caps 25 at its ends to serve as supports between the terminals of the tubular member 24 and the ends 20. The tubular member 24 is immovably coupled to the shaft by holding pins or like devices 26. By this arrangement, it will be obvious that when the shaft 18 is rotated, the drum will be rotated therewith.

Formed in the screening material 21 of the drum is a feed opening covered by a swinging cover 27 formed of the same screening material as the body of the drum. 75 The cover 27 is movably coupled to the body of the drum by hinges 28 or like devices so that the cover can swing upwardly through the opening 11, as shown by dotted lines in Fig. 1, to permit the material to be screened 80 to be inserted into the drum, and likewise permit the material to be discharged from the drum when the latter is reversed in position.

Extending through the casing 10, slightly 85 above the upper line of the screening drum, are holding rods 31—32. A flexible member, for instance a chain 33, is connected permanently at one end to the rod 31 and depends therefrom and around the lower face 90 of the screening drum and out through the opening 11 and is adapted to be connected by one of its links to a pin 34 extending from the upper face of the casing. By this means, the flexible member may be supported in constant engagement with the lower part of the drum while the latter is being rotated. Surrounding the body of the drum is a bearing band 35 which extends from the opposite edge of the opening 100 in the drum, while a section of a similar band material 36 is connected to the closure 27 of the drum, the two band portions 35—36 being in alinement circumferentially of the drum and with which the flexible member 105 33 engages constantly as the drum is rotated and thus prevents friction or wear between the wires composing the screen material and the flexible member.

By this simple arrangement, as the drum 110

is rotated, the flexible member operates in constant contact therewith and holds the cover 27 in closed position while the drum is moving through the lower half of its path, and thus prevents the escape of the contents of the drum. The drum may thus be rotated any required number of times to insure the complete screening of the material, the ashes and finer particles of the material passing through the screen material of the drum and of the receptacle 17. When the contents of the drum are to be discharged, the flexible element 33 is disconnected from the holding pin 34 and permitted to drop, thus releasing the closure 27, and when the drum is in its downward position the closure will open and permit the contents of the drum to escape into the receptacle 17 from which it may be discharged by withdrawing the receptacle which is drawer like in form.

When the material is to be deposited within the drum, the closure 12 is opened and the drum rotated until the closure 27 is moved into upward position when the latter may be also opened into the position shown by dotted lines in Fig. 1. A feed hopper 37 is then inserted through the opening 11 of the casing with its lower reduced end inserted through the opening in the drum. The hopper is supported by the edges of the opening 11, and in position to enable the material to be screened to be poured therethrough into the drum. The hopper is then removed and the closures 11-27 closed and the flexible element 33, which has been previously restored to its operative position, permits the drum to be rotated any required number of times without permitting the contents of the drum to escape. When the screening action is completed, the closure 27 may be released by releasing the flexible member, as before described.

In Fig. 4, a modification in the construction is shown, consisting in substituting for the drawer like receptacle 17 an inclined screen 38. The upper edge of the screen member 38 is bent around a holding rod 39 extending through the casing 10, while its lower edge terminates at the bottom of the opening 14. The sliding closure 15 thus serves as a cut-off to the material which may fall upon the screen 38, while the ashes and finer particles of the cinders pass through the inclined screen.

The improved device is constructed entirely of metal, preferably galvanized iron,

to prevent corrosion, and may be of any required size or capacity.

Preferably, a perforated support or 60 hanger 40 is connected to the casing to permit the latter to be suspended from a nail or other support when not in use.

Having thus described the invention, what is claimed as new is:

1. An apparatus of the class described comprising a casing, a screening drum mounted for rotation within the casing and having a feed opening, a movable cover for the feed opening, and a flexible element suspended within the casing and bearing against the drum to hold the cover in closed position during the rotation of the drum. 70

2. An apparatus of the class described comprising a casing having an opening, a screening drum mounted for rotation within the casing and having a feed opening, a movable cover for the feed opening, a flexible element suspended within the casing and bearing against the lower part of the drum to hold the cover in closed position against the drum while the drum is passing through the lower portion of its path, and a feed hopper supported in the opening of the casing and extending through the opening of the drum. 85

3. An apparatus of the class described comprising a casing, a screening drum mounted for rotation within the casing and having a feed opening, a movable cover for the feed opening, a bearing band extending around the body of the drum, a bearing band carried by the cover and in circumferential alignment with the bearing band of the drum, and a flexible element suspended within the casing and bearing against the bearing bands of the drum and its cover to hold the cover in closed position during the rotation of the drum. 90 95

4. An apparatus of the class described comprising a casing, a screening drum mounted for rotation within the casing and having a feed opening, a movable cover for the feed opening, a flexible element connected at one end within the casing and bearing against the drum, and means for detachably connecting the other end of the flexible element to the casing. 105

In testimony whereof I affix my signature in presence of a witness.

JULIUS T. FREY. [L.S.]

Witness:

W.M. H. McCLENAHAN.
